UNITED STATES PATENT OFFICE

2,574,800

SWIVEL

Karl W. Sköld, Ramnas, Sweden

Application May 16, 1949, Serial No. 93,627
In Sweden May 21, 1948

1 Claim. (Cl. 59—95)

1

The present invention relates to a swivel, i. e. a member connecting two chains' lengths intended to permit turning of one chain's length relatively the other one without jamming. This is mostly the case with an anchor chain, the "anchor part" of which—anchor with shackle and stray length—by means of a swivel is connected with the long length running over the capstan device.

When dropping the anchor, and also when heaving it, the chain mostly, due to the effect of the current on the anchor flukes, becomes so twisted or turned that it cannot run through the capstan device when hauled in. This may be particularly difficult and time wasting if the anchor has been dropped on deep water with a strong current going. In such cases the hauling must take place in steps with one or two men standing at the chain pipe ready to pry and turn the chain in correct position with iron crows, and of course chain and windlass will have to be stopped while this is performed.

However, said difficulties are remedied to a small degree only by the usual swivel, and therefore many ships are sailing without it. Imperfect function and high prices counteract the otherwise given compulsory use of it.

The grounds for the deficiencies of the customary swivel are to be found in its evidently primitive, friction furthering construction. Thus all pressure and bearing surfaces are completely uncovered and open for corrosion as well as for the entering of particles causing a strong friction, such as sand, mud or the like, according to the nature of the anchor bottom. This in connection with the abnormally high specific surface pressure on the small supporting surface of the pivot head—which carries the weight of the anchor and the stray length—results in a mostly permanent locking of the swivel motion.

The object of the present invention is to eliminate these drawbacks.

The object of the invention is mainly characterized in that around the pivot are mounted two (or more) bearing halves provided with annular flanges entering annular grooves in the pivot, said bearing halves being screwed into the sleeve and being locked against turning relatively same.

The invention is illustrated by an embodiment in the accompanying drawing, in which Fig. 1 is a plan view, partly in section, of a swivel according to the invention. Fig. 2 is a corresponding side view partly in section. Fig. 3 is a section along the line III—III in Fig. 1. Fig. 4 shows some details.

2

In the drawing, the numeral 1 designates a loop provided with a sleeve 2 having internal threads 3. 4 is a loop provided with a pivot 5. Said pivot 5 is provided with annular ribs 6. Two bearing halves 8, 9 together forming a bearing sleeve with internal annular grooves 7 corresponding to the ribs 6 are placed around the pivot 5, said bearing halves being provided with external threads 10 corresponding to the threads 3, and being screwed into the sleeve 2. At its termination towards the loop 4 the pivot 5 has a flange-like part 16 and an annular groove 11 for a packing 12. In a projection 13 on the sleeve 2 there is made a bore 14 extending along a chord, which bore also traverses one or both bearing halves 8, 9, and a pin 15, which is preferably somewhat bent and resilient and is inserted in the bore, prevents a pushing-out of the bearing halves. In the flange-like part 16 of the pivot 5 is provided a bore (or more bores) 18 extending in the direction of the axis and having internal threads 17 and a flange 19 which protrudes inwardly, and right in front of the bore (or bores) 18 a bore 20 is provided in one bearing half 8 (or in both bearing halves). A screw 21 with an axial pin 22 of a diameter smaller than that of the screw is screwed into the thread 17. A helical spring 23 is placed around the pin 22 between the flange 19 and the screw 21. At the mouth of the bore 18 center punch marks 24 are provided to prevent the screw from being screwed completely out. Directional marks 25 are provided in the flange-like part 16 of the pivot and in the sleeve 2 for indicating the relative angular position between the pivot 5 and the sleeve 2 or the bearing half 8 at which the bore 20 is located right in front of the bore 18.

In the sleeve 2 there is turned out a relatively large cavity 26 which constitutes a container for relatively highly liquid oil with a low point of solidification. Axial channels 27 are provided in the interior of the sleeve 2, and holes 28 and 29 respectively are bored in the bearing halves 8, 9 and in the pivot 5 to permit oil from the cavity 26 to float to the different bearing surfaces.

At the manufacture the swivel is assembled in the following way. The two bearing halves 8, 9 are placed around the pivot 5 of the loop 5, whereupon the screw 21 is screwed in so that the pin 22 enters the recess 20 in the bearing half 8, which for instance by means of grooves 27 is marked to show the position relatively the screw 22. The latter then serves as a claw-wrench for the tightening of the bearing halves

against the sleeve 1. Then the hole 14 is bored and reamed and the locking pin 15 is driven in so that the bearing halves 8, 9 are immovably locked to the sleeve 1. The directional marks 25 are then provided. Finally, the screw 21 is screwed up so far as permitted by the centre punch marks 24, whereby the pivot 5 becomes rotatable relatively the sleeve 1. The screw spring 23 secures that the screw 21 cannot tighten in the bore 20 again on account of shakings.

10

Having now described my invention, what I claim as new and desire to secure by Letters Patent is:

A swivel comprising a loop formed with an internally threaded sleeve integral therewith, a second loop formed with an integral pivot which extends into and is rotatable relative to said sleeve, a pair of externally threaded bearing halves disposed in an interspace between the sleeve and pivot portions respectively of the two loops and 20 provided with internal annular bearing flanges engaging annular bearing recesses in the pivot, said bearing halves being screwed into the internally threaded sleeve and means for locking said bearing halves against turning relative to 25 said sleeve, a screw having an axial elongation screwed with its head completely sunk into a threaded bore extending in the axial direction in said second loop provided with the pivot, which elongation of the screw is engageable with 30

a bore in the end of one of the bearing halves to lock the bearing halves and said second loop against rotation, and a coil spring surrounding said elongation of the screw and engaging the head thereof tending to prevent it from engaging the end of the bearing half and guiding the screw in the lateral direction in the bore.

KARL W. SKÖLD.
